COMBINED DISPLAY AND MATCH PACKAGE HOLDER

Gerhardt O. Lebrenz, North Tonawanda, N. Y.

Application October 24, 1940, Serial No. 362,649

7 Claims. (Cl. 206—33)

This invention relates to a combined display and match package holder.

The invention aims to provide, in a manner as hereinafter set forth, a device of the class referred to including provisions for not only holding a removable display, but also for removably holding a match package.

The invention further aims to provide, in a manner as hereinafter set forth, a device of the class referred to including provisions for connecting it to a match package of the book type, as well as provisions for making it possible for a person to view or look at a picture of a loved one, a friend or a pet when handling the package or when a match is removed and ignited.

The invention further aims to provide a device for the purposes set forth which is simple in its construction and arrangement, strong, durable and compact, readily installed with respect to a match package, distinctive in appearance, attractive, and comparatively inexpensive to manufacture.

Embodying the aims aforesaid and others which may hereinafter appear, the invention consists of the novel construction, combination and arrangement of parts as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is a rear elevation of a combined display and match package holder, in accordance with this invention showing the adaptation thereof with respect to a match package,

Figure 2 is a front elevation of the structure shown in Figure 1,

Figure 3 is an elevation looking towards the inner face of a match package when extended and showing the adaptation with the package of the device in accordance with this invention; the package and device being broken away at several points and the device partly shown in section.

Figure 4 is a section on line 4—4 Figure 1,

Figure 5 is a section on line 5—5 Figure 1,

Figure 6 is a section on line 6—6 Figure 3,

Figure 7 is a rear elevation of the blank from which the display holder is formed,

Figure 8 is a rear elevation of the blank from which the clamp is formed.

With reference to the drawing, there is shown a match package of the book type, which consists

5 of a body part 10 of strip-like form bent upon itself to provide a back 11 and a front or cover 12, and a fold 13 opposing the inner face of the lower portion of the back 11. The fold 13 is provided with a match igniting surface 14. The bend between the back 11 and front 12 is indicated at 15, and the bend between the back 11 and fold 13 is indicated at 16. Arranged between the back 11 and the fold 13 is a carrier 17 having integral therewith a series of matches 18 capable of being readily severed from the carrier. The carrier 17 is arranged in close proximity to the bend 16 and it is secured by holdfast means 19 to the back 11 and fold 13. The front 12 is of less length than the back 11 and its free end is capable of being inserted between the fold 13 and the lower portions of the matches for detachably holding the front closed. The foregoing match package is of the form now in general use and it is illustrated for the purpose of showing the adaptation therewith of the device in accordance with this invention.

25 The combined display and match package holder, in accordance with this invention includes a foldable carrier 20 of strip-like form and set up from any suitable material, such as leather or fabric. The carrier is positioned against the outer face of the body part 10 and it is of a width greater than the width of said body part. The end 21 of the carrier 20 is spaced inwardly from the free end 22 of the front 12. The other end 23 of the carrier 20 extends beyond the bend 16.

30 The front 12 and carrier 20 are connected together by a clamping element 24, preferably formed of thin bendable metallic material. The element 24 consists of a rectangular flat plate-like body 25 having integral with its sides a pair of oppositely disposed inwardly extending folds 26, 26 which overlap and are spaced from the outer face of body 25. The carrier 20 is inserted between the body 25 and the folds 26, 26. The element 24 is to be permanently secured to the end terminal parts 28^a of those portions 28^b of the carrier 20 which extend laterally in opposite directions from the said front 12 of the match package.

35 Any suitable means may be employed for securing the element 24 and carrier 20 together, and by way of example the said body 25 is swaged as at 28^c to engage in said terminal parts 28^a whereby the carrier and element 24 are secured together. It is to be understood that the folds 26, 26 may be swaged instead of the body 25, or that the said body 25 and the said folds may be swaged. That portion of the body 25 ad-

10 jacent the points of securance between such body and the carrier 20 is spaced from the inner face of the latter. The said front 12 of the match package is inserted through the aforesaid space whereby the match package is removably connected to the carrier. The foregoing arrangement provides for the easy introduction of the front 12 of the match package under element 24 and the carrier 20. The body portion 25 of the element 24 has an edge disposed slightly beyond the end 21 of the carrier 20.

15 The device includes a holder element for the display, which also constitutes a means for clamping the back 11 and carrier 20 together. The said element is generally indicated at 27 and is constructed from thin bendable metallic material. The element 27 comprises a rectangular body portion 28 formed in proximity to one end with a transversely disposed rectangular slot 29. Integral with the sides of the body portion 28 is 20 a pair of oppositely disposed folds 30, 31, which oppose the outer face of said body portion 28. Integral with the lower end of body portion 28 and opposing its outer face is a fold 32 arranged between the lower ends of the folds 30, 31. The ends of the fold 32 opposes the lower ends of the folds 30, 31 and the opposed ends of the folds 30, 31 and 32 are mitered, as at 33. The upper ends of the folds 30, 31 are squared. Formed integral with the upper part of the inner side edge of the fold 30 is a coupling strap 34, which extends at right angles to said fold 30 to a point across and beyond the upper portion of the outer face of the fold 31 and said strap is bent around the fold 31 and positioned against the upper part of the inner face of the body portion 28, as indicated at 35. The folds 30, 31, 32 and strap 34 coact to provide a frame positioned on the outer face of that portion of the carrier 20, which is disposed against the outer face of the back. That portion of the outer face of the carrier 20, which is opposed by the folds 30, 31 and 32 and the strap 34 constitutes the back of the aforesaid frame and is reinforced by said body portion 28.

25 The bends between the body portion 28 and folds 30, 31, 32 are indicated at 36 and they are of a width to space such folds from the outer face of the carrier 20. The frame provided in a manner as referred to is adapted to receive the object to be displayed and by way of example such object is shown as a photograph or picture and indicated at 37. The object 37 is removably mounted in the frame. There is also positioned in the frame a transparent panel 38 forwardly of the object 37. The object 37 and panel 38 are 30 removably mounted in the frame.

35 The slot 29 is provided for inserting the body part 10 of the match package between the carrier 20 and the aforesaid body portions 25 and 28, which permits of removably connecting the 40 match package to the device.

45 The body portion 28 of the element 27 below the slot 29 is formed with a pair of spaced outset portions 39, which constitute stops and function to prevent the match package from slipping out of the device. The stops 39 are arranged in the path of the bend 16 when the match package is 50 removably connected to the device.

55 The element 27 is formed of what may be termed an outer and an inner side or outer and inner portion. The outer side is of frame-like contour for removably confining the object to be displayed against the outer face of the carrier 20. The inner side is in the form of a sheet-like body 60 for extension across the inner face of the body

part 10 of the match package. The said sides are so related to removably connect the carrier 20 and body part together.

65 Although the elements 24 and 27 have been referred to as being formed from metallic material, yet it is to be understood that either or both may be in the form of a one-piece molded plastic body of Celluloid or Bakelite of the desired color.

70 What I claim is:

1. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, and said inner side being in the form of a sheet-like body adapted to extend across the inner face of the said other end portion of the body part of the package, the said inner and outer sides being so related for connecting said carrier to the body part of the package.

75 2. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, and said inner side being in the form of a sheet-like body adapted to extend across the inner face of the said other end portion of the body part of the package, the said inner and outer sides being so related for connecting said carrier to the body part of the package, said inner side being formed with a slot adapted for the passage of the body part of the package to oppose the inner face of the carrier.

80 3. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, said inner side being in the form of a sheet-like body adapted to extend across the inner face of the said other end portion of the body part of the package, the said inner and outer sides being so related for connecting said carrier to the body part of the package, said inner side being formed with a slot adapted for the passage of the body part of the package to oppose the inner face of the carrier, and said inner side being formed with

stops adjacent said slot adapted to arrest the shifting of the match package from the device.

4. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, and said inner side being in the form of a sheet-like body adapted to extend across the inner face of the said other end portion of the body part of the package, the said inner and outer sides being so related for connecting said carrier to the body part of the package, said frame consisting of a pair of side members, a bottom member and a top member, said top member being in the form of a bendable coupling strap integral with one side member and overlapping the other side member.

5. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, and said inner side being in the form of a sheet-like body adapted to extend across the inner face of the said other end portion of the body part of the package, the said inner and outer sides being so related for con-

necting said carrier to the body part of the package, said frame consisting of a pair of side members, a bottom member and a top member, said top member being in the form of a bendable coupling strap integral with one side member and overlapping the other side member, said inner side formed with a slot adapted for the passage of the body part of the package to oppose the inner face of the carrier.

6. A combined display and match package holder comprising a bendable carrier adapted for disposing against the outer face of the bendable body part of a match package, a clamp adapted to removably connect an end portion of the carrier to an end portion of the body part of the match package, a combined clamping and display holding element adapted to connect the other end portion of the carrier to the other end portion of the body part of the match box, said element including an inner and an outer side, said outer side being in the form of a frame disposed on the outer face of the carrier for removably securing the object to be displayed against said face, and said inner side being in the form of means extending over the inner face of the said other end portion of the body part of the package, the said inner and outer sides being so related for connecting said carrier to the body part of the package.

7. A holder for book-match or the like packages, including in combination, an elongated foldable carrier element, a rigid frame, and a rigid clamping means, said clamping means being disposed on the inner face of the carrier element and secured to an end portion of the latter in proximity to each side edge of the carrier and providing for the retention of the flap of the package against the carrier element, said frame being open at one side for the reception of a photograph or like indicia for display in the frame, and said frame being secured with the other end of said carrier to be carried thereby, said frame being further provided with means for the retention of the body part of said package.

GERHARDT O. LEBRENZ.
